(57) **CLAIM**

The ornamental design for a hand for a watch or clock, as shown and described.

DESCRIPTION

FIG. 1 is a front elevation of a hand for a watch or clock showing my new design; and,

FIG. 2 is a front elevation of the hand for a watch or clock shown in a different position.

The watch, portions of the watch band, the dial and the hands that are shown in broken lines do not form part of the claimed design.

1 Claim, 2 Drawing Sheets

FIG.1

FIG.2
